Primary Examiner — April Rivas*Assistant Examiner* — Dustin Andrew Griffith(74) *Attorney, Agent, or Firm* — Umberg Zipser LLP(57) **CLAIM**

The ornamental design for a saddle backpack as shown and described.

DESCRIPTION

FIG. 1 is a top, front, left-side perspective view of the saddle backpack showing my new design.

FIG. 2 is a bottom, rear, right-side perspective view thereof.

FIG. 3 is a front elevation view thereof.

FIG. 4 is a rear elevation view thereof.

FIG. 5 is a left-side elevation view thereof.

FIG. 6 is a right-side elevation view thereof; and,

FIG. 7 is another perspective view showing the saddle backpack in a configuration of use.

The broken lines in FIGS. 1-7 are for the purpose of depicting stitching and does not form part of the claimed design.

1 Claim, 7 Drawing Sheets(56)
